UNITED STATES PATENT OFFICE

2,366,511

SMOKESTACK FOR MOVABLE POWER PLANTS

Vladimir G. Frisk, Schenectady, N. Y., assignor to
General Electric Company, a corporation of
New York

Application June 12, 1943, Serial No. 490,630

2 Claims. (Cl. 285—183)

The present invention relates to smokestacks for movable power plants, especially of the kind which are to be moved on railroad tracks. Bridges and other overhead obstacles ordinarily necessitate making the smokestack of several parts which can be readily assembled and dismantled.

The object of my invention is to provide an improved smokestack especially adapted for movable power plants.

For a consideration of what I believe to be novel and my invention, attention is directed to the following description and the claims appended thereto in connection with the accompanying drawings.

In the drawing Fig. 1 illustrates a movable power plant embodying my invention; Fig. 2 shows a sectional view of the smokestack of Fig. 1 to an enlarged scale; Fig. 3 shows such smokestack in operating position; and Figs. 4 and 5 are detail views of certain parts of Fig. 3.

The movable power plant arrangement shown in Fig. 1 comprises a plurality of trucks 10 which may be moved along a railroad track. These trucks are connected by and act as a support for a frame 11 which forms a foundation for power plant apparatus including a boiler with a combustion and convection chamber 12 and a smokestack arrangement 13 for conducting gases discharged from the combustion and convection chambers to atmosphere and aiding to induce sufficient draft in the combustion chamber.

The smokestack arrangement comprises a plurality of substantially cylindrical members or smokestack cylinders. In the present instance I have shown three such cylinders 14, 15 and 16. These cylinders are of successively smaller diameters so that they may be telescoped into each other, as shown in Fig. 2. The lower cylinder 14 is rigidly secured to the frame or foundation of the power plant and enclosed by a heat-insulating wall 17. The lower end of the cylinder 14 forms an opening 18 for receiving gases discharged from the combustion and convection chambers 12 of the boiler or elastic fluid generator. The intermediate cylinder 15 is supported on and secured to the lower cylinder 14 by means of a special coupling and centering device 19 and the upper cylinder 16 is supported and centered on the upper end of the intermediate cylinder 15 by a similar coupling and centering device 20.

Each coupling and centering device 19 and 20 comprises a flat ring 21 and two cylinders 22 and 23 of different diameters secured to the lower face and upper face respectively of the flat ring

21. In order to assure a firm connection, the inner diameters of the cylinders 22 and 23 are slightly smaller than the corresponding outer diameters of the lower cylinder 14 and the intermediate cylinder 15 respectively. Each of the coupling devices 19, 20 is made of two halves or segments 24 and 25 provided with flanges in the form of brackets 26 at the ends of each half for securing the halves together and thereby bringing them into intimate contact with the adjacent portions of the smokestack cylinders to be connected. The coupling device has a plurality of circumferentially spaced radial pins 27 for projecting into openings 28 in the adjacent end portions of the smokestack cylinders. The structure as a whole is fabricated. The different parts of each coupling device as fused together by welds. When assembled the flat ring 21 rests on the upper end of the lower smokestack cylinder 14 and the lower end of the intermediate cylinder 15 rests on the flat ring 21. The coupling cylinders 22, 23 form gripping contact with the corresponding ends of the smokestack cylinders 14 and 15 respectively.

25 During assembly the intermediate cylinder 15 is held in proper position with its lower end near and facing the upper end of the lower cylinder 14. Thereupon the two halves 24 and 25 of the coupling device 19 are applied from opposite sides 30 and are radially moved toward each other until the pins 27 project into the openings 28 of the smokestack cylinders. Finally the two halves of the coupling device are drawn against each other by tightening bolts 29 projecting through the flanges or brackets 26 at adjacent ends of the two halves 24, 25.

35 The openings 28 in the upper end of the intermediate cylinder 15 also facilitate the application of hooks for lifting such cylinder. The upper cylinder is provided with cross bars 30 in its upper end to facilitate lifting thereof. The coupling device 20, as pointed out above, is similar to the device 19 except that the first is of smaller diameter corresponding to the smaller diameter 40 of the upper smokestack cylinder 16. When disassembled, that is, while the power plant is moved or to be moved on tracks, the several cylinders are telescoped into each other, as shown in Fig. 2, and their upper ends are enclosed by an enclosing cover 31 with a skirt 32 surrounding the upper ends of the cylinder. The cover 31 is securely fastened to a plurality of circumferentially spaced brackets 33 on the upper or inner cylinder 16 by means of bolts 34.

45 Having described the method of operation of

my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. A coupling and centering device for cylinders which may be telescoped into each other, said device comprising a flat ring, cylindrical members of different inner diameters secured to op-

posite sides of the ring, and radial pins secured to said members.

2. A coupling and centering device for two cylinders of different diameter comprising a flat ring and two cylindrical members of different diameter concentrically secured to opposite sides of the ring, said ring and cylindrical members being made in two halves, and means on each half for securing the halves together.

VLADIMIR G. FRISK.
